Attorneys.

UNITED STATES PATENT OFFICE.

HERBERT J. GRAHAM, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

HEADLIGHT.

Application filed May 10, 1923. Serial No. 637,965.

My invention relates to improvements in headlights whereby interference by dust and moisture with the desired illumination is reduced to a minimum.

5 Heretofore the efficiency of headlights has been impaired by the entrance of dust and moisture into as also the condensation of moisture within the case and the deposit of the same upon the lamp, the reflector and 10 the glass through which the rays are projected to effect the desired illumination.

It is the primary purpose of this invention to provide a headlight having a case that will effect the maximum exclusion of 15 dust and moisture while discharging any moisture that may be condensed or otherwise collected therein, to the end that the highest degree of efficiency of illumination may be obtained, without impairment by 20 such dust and moisture.

The characteristic features of my invention are embodied in the headlight set out in the following description and the accompanying drawings in illustration thereof.

25 In the drawings, Fig. 1 is a broken side elevation of the said headlight embodying the invention; Fig. 2 is a sectional view on the line 2^x—2^x of Fig. 1; Fig. 3 is a sectional view on the lines 3^x—3^x of Fig. 1, similar to 30 a view on the line 3^y—3^y of Fig. 1; Fig. 4 is a perspective view on an enlarged scale of the clamp illustrated in Fig. 3; and Fig. 5 is a perspective view on an enlarged scale of the filtering disk illustrated in Fig. 3.

35 The headlight illustrated comprises the cylindrical case body 1 having the tightly closed back 2, front door 3 and side doors 4, each provided with tight joints adapted for obtaining the maximum exclusion of dust 40 and moisture and for preventing deposit thereof upon the glass 5 of the front door, the glass 6 of the side doors, the lamps 7 and 8 whose rays are projected through the respective doors, and the reflector 9 for projecting the rays of the lamp 7.

The door 3 is provided with the maximum degree of tightness by means of the frame seat 10 of angular cross-section in which is held a gasket or packing 11 of U-shaped 50 cross-section having a tightly fitted engagement with the periphery of the glass 5. The frame flange 12 extends over and around the forward end of the body 1 against the pack-

ing ring 13 of rounded cross-section which is held in the seat 14 fixed to the periphery 55 of the body slightly to the rear of the forward end thereof. This door is held in closed position with the flange 12 pressed tightly against the packing 13 and the latter is expanded, by means comprising the stud 15 provided with the roller 16 carried by the body 1 and the cam lever 17 fulcrums on the stud 18 carried by the door 3.

The door 4 is provided with the maximum degree of tightness by means of the frame 65 seat 19 of angular cross-section in which is a gasket or packing 20 against which the glass 6 is pressed by the glass 6' adapted for holding numbers to be shown through the glass and the holder 20' pressed against the 70 plate and secured to the door frame. The door frame flange 21 extends inwardly, lies within the flange 22 of the frame 23 fixed to the body 1 and bears against the packing 24 of rounded cross-section which is held within 75 the seat 25 integral with the part 23. The doors 4 are held in closed position, by means of the door hinges 25', door yokes 26, and the bolts 27 pivoted to the frames 23 and having the nuts 28 which act against the 80 yokes, the parts 21 being thereby tightly pressed against the parts 24 to expand the latter.

The bottom of the body 1 and the bottom of the door 3 are each provided with an 85 aperture 29, placed at the lowest parts thereof. A body of filtering material 30, suitably a laminated disk of textile material, that will absorb and pass moisture which may collect in the case while preventing the passage of dirt and dust, is held within the case over each aperture 29 by an open holder 31. This holder or fixture as shown comprises a ring adapted for engaging the periphery 90 of the disk while leaving the central body 95 portion thereof exposed, feet 32 adapted for resting upon the bottom of the case if desired and holding the disk in place while permitting such disk to perform its filtering function beneath the ring, and the lugs 33 100 adapted for securing the holder to the body 1 and to the frame of the door 3.

Thus a tight case is provided that will prevent the entry of dust, dirt and moisture while discharging any water that may be 105 found therein.

Having described my invention, I claim:
A headlight having in the bottom thereof
an aperture, a body of fibrous filtering mate-
rial (adapted for passing water from said
case through said aperture and preventing
the passage of dust) disposed within said
case and said aperture, and a ring having

thereon lugs for engaging it to said case and
feet for engaging said material around said
aperture.

In testimony whereof I have hereunto set
my name this 26 day of March, 1923.

HERBERT J. GRAHAM
